UNITED STATES PATENT OFFICE.

NEWTON E. PHILLIPS, OF SHELBY, MICHIGAN, ASSIGNOR, BY DIRECT AND MESNE ASSIGNMENTS, OF ONE-HALF TO CHARLES L. CHURCHILL AND ONE-SIXTH TO RET. O. HAMILL, BOTH OF SHELBY, MICHIGAN.

OIL-BURNER.

1,230,772.

Specification of Letters Patent. Patented June 19, 1917.

Application filed October 21, 1916. Serial No. 126,961.

To all whom it may concern:

Be it known that I, NEWTON E. PHILLIPS, a citizen of the United States, residing at Shelby, in the county of Oceana and State 5 of Michigan, have invented certain new and useful Improvements in Oil-Burners; and I do hereby declare the following to be a full, clear, and exact description of the invention, such as will enable others skilled 10 in the art to which it appertains to make and use the same.

This invention relates to improvements in an oil burner and has for its primary object the provision of vaporizing means between a fuel supply and the burner to vaporize the fuel prior to entering the burner. 15

Another object of this invention is to provide a vaporizing drum connected to a fuel supply and to a burner for vaporizing the fuel prior to entering the burner and which is so located, that it will receive heat from the burner to thoroughly heat the same whereby the fuel contained therein will be vaporized. 20

A further object of this invention is to provide a fuel heating tube connected to the vaporizing drum and having openings therein to allow the vaporized fuel to escape therefrom and to be ignited and over which 25 are positioned sleeves for controlling the air supply, whereby the danger of extinguishing the flame is obviated by too great an air supply.

A further object of this invention is to provide a plurality of openings at the upper ends of the sleeves for permitting air to the flame and said sleeves further having their lower ends so constructed as to admit air upwardly therethrough for further supplying the same with air. 35

A still further object of this invention is the provision of an oil burner of the above stated character which shall be simple, durable and efficient, and which may be manufactured and sold at a comparatively low cost. 45

With these and other objects in view as will become more apparent as the description proceeds, the invention consists in certain novel features of construction, combin- 50

nation and arrangement of parts as will be hereinafter more fully described and claimed.

For a complete understanding of my invention, reference is to be had to the following description and accompanying drawings, in which— 55

Figure 1 is a top plan view of an oil burner, constructed in accordance with my invention, 60

Fig. 2 is a longitudinal sectional view taken on the line 2—2 of Fig. 1, 65

Fig. 3 is a transverse sectional view taken on the line 3—3 of Fig. 2, 70

Fig. 4 is a vertical sectional view illustrating the means of securing the sleeves upon the tube, and 75

Fig. 5 is a vertical sectional view of a modified form of sleeve illustrating the means for regulating the air supply upwardly through the sleeve. 80

Referring in detail to the drawing, the numeral 1 indicates a substantially rectangular base having downwardly depending flanges 2 formed on the edges thereof which are adapted to support the base 1 within the fire box of a stove, furnace or the like in any well known manner. A pair of air chambers 3 are formed at each end of the base 1 by upwardly and inwardly inclined walls 4 which support a substantially U-shaped fuel heating tube 5 which has one end closed by a cap 6 and the other arm portion of the substantially U-shaped fuel heating tube 5 is disposed in a plane above the air chambers 3 and is supported by a bracket 7 secured to the base 1 as indicated at 8'. The tube 5 is provided with openings 8 for allowing fuel to escape from the tube. 85

A substantially L-shaped drum 9 has a fuel supply pipe 10 connected adjacent its lower end thereof for supplying the same with liquid fuel and has its upper end threaded to the substantially U-shaped fuel heating tube 5 as illustrated at 11. The base 95 1 has secured thereon asbestos or like material 12 between the walls 4 of the air chambers 3 whereby liquid fuel may be poured thereon and ignited for heating the tube 5 and the drum 9 to vaporize the liquid 100

fuel therein, whereby the vaporized fuel will pass out through the openings 8 and become ignited and the heat from the flame will be directed against the upper arm portion of the tube 5 and the drum 9 so as to thoroughly vaporize the fuel before reaching the openings 8.

Cylindrical sleeves 13 have oppositely disposed elongated slots 14 in their lower ends to receive the tube 5 within the air chambers 3 and the sleeves 13 are held thereon by set screws 15 threaded into the walls of the sleeves 13 and turned into engagement with the tube 5 as clearly illustrated in Fig. 4. The upper ends of the sleeves 13 are provided with a plurality of perforations 16 for emitting air to the flame from the openings 8 of the tube 5 and the upper ends of the sleeves 13 are separate sections as illustrated in Fig. 4 and are secured together by hinges 17 and spring clasps 18. Cleaning arms 19 are pivoted to the upper sections of the sleeves 13 as illustrated at 20 and have their free ends provided with tapering projections 21 which are adapted to be moved into engagement with the openings 8 by handles 22 for removing soot or carbon which may accumulate within the openings 8.

Asbestos collars 23 are secured about the lower ends of the sleeves 13 for closing the elongated slots 14 preventing air from passing into the sleeves by way of said slots and which air will be compelled to pass upwardly from the lower open ends of the sleeves and about the tube 5 to supply the flame from the openings with a correct supply of air.

In operation, liquid fuel passes into the vaporizing drum 9 from the pipe 10 and into the substantially U-shaped fuel heating tube 5 and outwardly through the openings 8 and by thoroughly saturating the asbestos 12 with liquid fuel and igniting the same, the tube 5 and drum 9 will be heated, vaporizing the liquid fuel therein, which vaporized fuel will pass outwardly through the openings 8 and become ignited within the sleeves 13 which will furnish air to the flame from the vaporized fuel passing through the openings 8 and which flame will heat the upper arm portion of the substantially U-shaped tube 5 and the drum 9 to thoroughly vaporize the liquid fuel before reaching the openings 8. The flames from the vaporized fuel passing through the openings 8 are furnished with air through the perforations 16 of the upper sections of the sleeves 13 and through the lower open ends of the sleeves as clearly illustrated in Fig. 2.

Referring to my modified form of sleeve as illustrated in Fig. 5, it consists of an upper perforated section 24 and a lower section 25 which is constructed of flexible material and has oppositely disposed elongated slots 26 therein. The upper and lower sec-

tions are secured together by a hinge 27 and a spring catch 28. The lower section of the sleeve is positioned over the tube 5 by allowing said tube to pass upwardly through the elongated slots 26 and is held thereon by a bolt 29 passing through the lower section 25 of the sleeve and receiving a nut 30 upon its threaded end, whereby the lower ends of the section 25 may be moved toward and from each other to control the in-flow of air upwardly through the sleeve for supplying the flame within the perforated section 24 with the correct amount of air.

While I have shown and described the preferred embodiment of my invention, it will be understood that minor changes in construction, combination and arrangement of parts may be made without departing from the spirit and scope of the invention as claimed.

Having thus described my invention, what I claim is:

1. An oil burner comprising a base, air chambers formed in each end of said base, a substantially U-shaped tube carried by said base and extending through the air chambers, said tube having openings within the air chambers, a vaporizing drum connected to the tube, a fuel supply connected to the drum, and cylindrical sleeves carried by the tube and located within the air chambers for supplying air to the flame.

2. An oil burner comprising a base, air chambers formed in each end of said base, a tube carried by said base and extending through the air chambers and having openings within the air chambers to allow fuel to escape from the tube and become ignited, a vaporizing drum carried by said tube, a liquid fuel supply connected with said drum, cylindrical sleeves having elongated slots in their lower ends to receive the tube to locate said sleeves within the air chambers, and means for securing the sleeves to the tube.

3. An oil burner comprising an auxiliary heating base, air chambers formed in each end of said base, a tube carried by said base and extending through the air chambers and having openings therein for allowing fuel to escape from the tube and become ignited, a vaporizing drum carried by the tube, a fuel supply connected to said drum, sleeves having their lower ends provided with elongated slots to receive the tube to position said sleeves within the air chambers, said sleeves having perforations therein for admitting air to the flame, and bolts extending through the lower ends of said sleeves for controlling the inflow of air upwardly through the sleeves.

4. An oil burner of the type set forth including a burner tube provided with a fuel outlet opening, and a sleeve consisting of upper and lower sections hinged together

and surrounding said opening and extending above and below said tube.

5. An oil burner of the type set forth including a burner tube provided with a fuel outlet opening, a sleeve having slots therein and surrounding said opening, and a bolt extending through the sleeve.

In testimony whereof I affix my signature in presence of two witnesses.

NEWTON E. PHILLIPS.
